UNITED STATES PATENT OFFICE.

EDISON E. RANDALL, OF KANKAKEE, ILLINOIS, ASSIGNOR TO PARAMOUNT KNITTING COMPANY, OF CHICAGO, ILLINOIS, A CORPORATION OF ILLINOIS.

KNITTING-MACHINE.

1,166,077.

Specification of Letters Patent. Patented Dec. 28, 1915.

Application filed October 6, 1913. Serial No. 793,554.

To all whom it may concern:

Be it known that I, EDISON E. RANDALL, a citizen of the United States, residing at Kankakee, county of Kankakee, State of Illinois, have invented an Improvement in Knitting-Machines, of which the following description, in connection with the accompanying drawing, is a specification, like characters on the drawing representing like parts.

This invention relates to means for taking up the knitted web in a knitting machine and is more particularly designed for use in an automatic knitting machine in which the completed article such as a stocking, is knitted from one end to the other entirely automatically and in which the successive stockings are united to form one continuous web. In all such work it is necessary to secure a sufficient tension on the fabric for casting off the stitches from the needles in action at all times whatever may be the character of work being performed upon the machine or whatever change may be made from one to another kind of work during the knitting operation.

The mechanism of this invention is particularly useful in securing the requisite tension on the fabric for casting off the stitches from the needles in action where a change is made from plain to ribbed work after the formation of pockets such as for the toe or heel in the plain work.

While the invention is adapted for use as a part of various types of knitting machines it is herein illustrated as embodied in a machine of the type shown in re-issue patent to Huse and Huse, No. 12,917, granted February 9, 1909, or of the type shown in the pending application of Randall, No. 686,762, filed March 28, 1912. In the more elaborate forms of this machine that are designed for the knitting in one continuous web of a series of stockings automatically and completely two sets of needles such as the dial and cylinder needles are employed and the machine is arranged to knit as required either ribbed, plain circular, or reciprocating work.

The present invention relates to what is usually termed the auxiliary take up mechanism because it is particularly adapted for use in connection with another or main take up mechanism for the web.

The object of the invention is to provide

such a take up mechanism that will unerringly catch or seize the web at the desired point, shall move downwardly placing sufficient tension upon the web but without tearing, stretching, or injuring the web, which shall continue in action for a predetermined period and shall be automatically restored or elevated to the web seizing or catching position and in which the entire operation of the mechanism shall be under the control of suitable pattern mechanism.

The nature of the invention will appear more fully from the accompanying description and drawings and will be particularly pointed out in the appended claims.

The drawings illustrate only so much of a knitting machine as is necessary to a disclosure and understanding of the present invention. As the structural features of the present invention are concerned entirely with the take up mechanism it is not necessary herein to illustrate or describe the part of the knitting machine particularly concerned in the formation of the web itself.

The drawings represent a specific embodiment of this invention with the machine shown in a somewhat diagrammatic and simplified manner. In order that the invention may be clearly and simply disclosed it is to be understood however that the construction even of the preferred form, the arrangement of the various elements, their operation and location, are dependent upon the particular type of knitting machine and their structural requirements.

In the drawings: Figure 1 is a front elevation of so much of a knitting machine as is necessary to an understanding of the invention; Fig. 2 is a left hand side elevation partially in cross section taken on the line $a-a$ of Fig. 1; Fig. 3 is a detail in transverse cross section to show the latch element; Fig. 4 is a left hand side elevation partially in cross section of the portion of the machine and web at the seizing or catching position of the take up; Fig. 5 is a front elevation of a portion of the mechanism shown in Fig. 4.

The machine as shown comprises a suitable frame work having the legs 1, the top 2, and the central tie plate 3, from which frame work are supported the various elements in which the form disclosed by this invention are embodied.

The usual needle cylinder carrying the

usual cylinder needles is indicated at 4, the dial plate carrying the usual dial needles at 5; the respective sets of needles, their operating instrumentalities and the various instrumentalities required in the formation of the knitted web are not herein illustrated as they may be of any familiar and desired type.

The main shaft of the machine is shown 10 at 6, and is provided with fast and loose pulleys 7, and 8, respectively. An auxiliary shaft 9, is mounted transversely near the top of the frame work in suitable bearings and driven from the main shaft 6 by suitable driving connections such as the gears 10 and 11. The main shaft 6 through the beveled gear 12 and its connections not necessary to illustrate, may operate the needles, while the auxiliary shaft 9 is shown as carrying at its left hand end a pulley 13, transmitting power through a belt 14 to a pulley 15 on a shaft 16, which shaft is provided with a worm 17, engaging a worm wheel 18, for operating the grooved roughened rollers 19 of an ordinary form of main take up mechanism for the knitted web. This main take up mechanism need not be described in detail because when employed its function is similar to that of the main take up described 30 in the before mentioned re-issue patent and pending application.

The knitted web is indicated in Fig. 4 at 20 and extends from the interior of the cylinder 4 vertically downward through the main take up 19 which when used draws the knitted web yieldingly through the machine but not so as to place more tension than necessary upon the web, the belt 14 slipping on the pulleys 13 and 15 when there 40 is an undue amount of resistance.

A suitable pattern mechanism is diagrammatically illustrated in the barrel 21, provided with cam surfaces and pins and carried by the pattern shaft 22, journaled in 45 the standard 23, projecting from tie plate 3 and which may be operated from the main shaft in a manner more fully disclosed in the before mentioned pending application of Randall. This pattern mechanism may 50 be connected to the main take up to control the time and extent of action thereof upon the knitted web in a suitable manner, as for example as shown in the before-mentioned patent. In the construction illustrated lever 55 100 fulcrumed at 101 on the frame is connected by a link 102 on the frame of the main take up and is controlled by cam surfaces on the pattern mechanism 21 to raise the main take up off the web and bring the 60 brake shoe 103 and the pulley 15 into contact but these features are not involved in the present invention and further detailed description is unnecessary.

The auxiliary take-up in which the present invention is embodied comprises a hook

or grab shown as a long rod 24 provided at its upper end with downwardly inclined projecting teeth 25. The rod 24 is mounted to slide vertically in a fixed path with respect to the needle cylinder and for that purpose is shown as guided in and sliding through the bracket 26 secured to the needle cylinder and in and through the tie plate 3.

In order to insure the knitted web being seized by the hooks 25 of the grab or auxiliary take up a web deflector is provided to press the web against the grab. This device is located directly beneath the knitting point so that the knitted web may be seized as soon after its formation as practicable. 70 80 This deflector is shown as a U shaped member 27 secured at the bottom of the dial plate 5 and arranged so that the hooks of the grab will pass between its depending arms 28. These arms are bowed or bent outwardly toward the grab as clearly shown in Fig. 4. The web is thus held out or deflected toward the grab as the hooks 25 press in and catch the web.

The downward movement of the grab is 90 effected yieldingly so that the web will not be torn or injured and for this purpose a coiled spring 29 surrounds the lower end of the rod 24 abutting against the tie plate 3 at the top and the pin 30 in the rod at 95 the bottom. A yielding stop or buffer is further provided to break the shock of the sudden seizure of the web by the grab and partially relieve the web of the weight of the grab as it goes into action. In the form 100 illustrated this stop or buffer comprises an arm 31 pivoted at 32 to the framework and projecting in the path of a stud 33 on the rod 24. A coiled spring 34 holds the buffer yieldingly upward against a stop 35 and in a 105 substantially horizontal position. When the grab seizes the web and starts to descend the projection 33 strikes the buffer 31 and the buffer gives yieldingly downward against the tension of the spring 34 until 110 the projection 33 slides off from its other end. The buffer is rounded off as shown at 36 and there is sufficient lateral yield or 115 lost motion in the rod 24 that when the grab ascends the projection 33 will slide over the end of the buffer to a position above the same.

The grab is elevated step by step to bring it into its web seizing position and is then 120 automatically, or by the control of the pattern mechanism, released to seize and hang yieldingly upon the web to apply the requisite tension. A preferred form of mechanism for securing this movement of the grab is shown in the drawings.

A pawl carrier 37 shown as two plates secured together at the four corners is mounted to slide loosely on the rod 24 and has pivoted therein at the lower end a pawl 38 adapted to engage in the teeth 39 on the 130

adjacent edge of the rod 24. This pawl carrier is supported and given a vertical reciprocating movement by an eccentric strap 40 pivoted at its lower end 41 to the pawl carrier and surrounding at its upper end an eccentric 42 on the main shaft 1. The pawl is provided with an upwardly extending tail 43 engaged by a spring 44 secured to the back of the pawl carrier 37 and the pawl is thus held up against the rod 24.

10 The bracket 26 has pivoted thereon for horizontal movement at 45 a latch 46 which engages the teeth of the rod 26 and acts as a 15 deterrent to hold the rod from downward movement as it is elevated by the pawl 38. The rearwardly projecting arm 47 of the latch engages the tail 43 of the pawl while the forwardly projecting arm 48 of the latch is normally held by a spring 49 against 20 a vertical edge of the bracket 26, the arrangement being such that when the latch is in this position and as illustrated in Figs. 1 and 3 the pawl 38 will be in engagement with the teeth of the rod 24. An arm 50 is mounted on the face of the bracket 26 and engages the arm 48 of the latch. A stop 51 limits the movement in one direction of the arm 50. This arm 50 is given movement to operate the latch and for that purpose is shown as part of a bell crank lever fulcrumed at 52 and having its end pivotally connected to a vertically arranged link 53 in turn connected to a horizontally arranged link 54 which in turn is pivoted at 25 55 to a projection 56 from some rigid portion of the machine such as the needle cylinder. The link 54 carries a projection 57 in the path of a suitable cam 58 carried by the barrel 21 of the pattern mechanism.

30 40 The operation of the mechanism will now be apparent. The grab normally occupies its elevated position with the hooks 25 directly below the knitting point and with the knitted web sliding over the hooks and held 45 deflected by the deflector 27. The latch occupies the position shown in Fig. 3 of the drawing in engagement with the tooth of the rod 24. When it is desired that the grab shall come into action the pattern mechanism is so arranged as to bring a high part 50 of the cam 58 beneath the projection 57 thus through the connections described throwing the arm 50 to the right swinging the latch 55 on its pivot, thus withdrawing from engagement with the tooth on rod 24 and pressing to the left the pawl 38 and throwing it from engagement with the teeth 39 on the rod 24. The grab at once moves downward under the influence of the spring 29, 60 the teeth 25 seizing the web, and the shock of the downward motion is absorbed by the buffer 31 in the manner described. The knitting now continues with the grab hanging on the web and moving down yieldingly 65 under the influence of the spring 29 until

the desired action of the grab is completed which may be determined by a stop thereon, such as the projection 33, engaging a fixed portion of the frame such as the tie plate 3.

70 When the grab is to be elevated the projection 57 rides off on to a low part of the cam 58 and the spring 49 then acts to return the latch to the position shown in Fig. 3, thus allowing the pawl to come into engagement with the teeth 39 on the bar 24.

75 The pawl carrier 37 is continuously reciprocating by reason of its connection with the eccentric 42 so that the grab is gradually fed upward into its elevated position which is reached when the pawl reaches the lowermost tooth on the rod 24. Thereafter the grab has a very slight movement due to the engagement of the pawl with the lowermost tooth which in no way affects the knitting.

80 In the type of machine illustrated when the machine has completed the knitting of the heel pouch and is just beginning ribbed knitting the dial needles having come into action it is necessary to place more tension upon the web to secure the proper casting off of the stitches from the needles in action during ribbed knitting. If the main take up were the only instrumentality applying tension to the web at this time the tension would be unequal, throughout the courses of 85 the knitting at the knitting point because of the existence of the heel pouch and imperfect knitting would result. It is at this time that the grab comes into action and moves downward yieldingly and independently of 90 the main take up, thus producing sufficient tension on that side of the web which it 95 grips to equalize the tension throughout the web. The grab remains in action until the ribbed knitting has progressed to such an 100 extent that the tension exerted by the main take up will be sufficiently equal throughout the circular courses of the knitting at the knitting point when the downward movement of the grab will be stopped, thereupon 105 the mechanism acts to restore the grab to its original position.

110 Having fully described my invention what I claim as new and desire to secure by Letters Patent is:—

115 1. In a circular knitting machine the combination of a take up device mounted to slide at one side of the web and to catch in one side of the web upon its downward movement, a pivotally mounted arm, means for holding the arm yieldingly upward and means on the take up device for engaging the arm during the first portion of the downward movement of the take up device whereby the weight of the take up device is partially and yieldingly sustained by said arm during the first portion of the downward movement to prevent injury to the web.

120 2. In a circular knitting machine the combination of a take-up device mounted to

- slide at one side of the web and to catch in one side of the web upon its downward movement, a buffer supported on the frame, means for holding the buffer yieldingly upward, and means on the take-up device for engaging the buffer during the first portion of the downward movement of the take-up device whereby the weight of the take-up device is partially and yieldingly sustained by said buffer during the first portion of the downward movement to prevent injury to the web.
3. In a circular knitting machine the combination of a take up device mounted to slide at one side of the web and to catch in one side of the web upon its downward movement and means to press the web toward the said device at its web catching position.
4. In a circular knitting machine the combination of a take up device mounted to slide at one side of the web and to catch in one side of the web upon its downward movement, and a web deflector located inside the web to deflect the web toward the said device in its web catching position.
5. In a circular knitting machine the combination of a grab provided with a toothed head at its upper end and mounted to slide at one side of the web and to catch in the web upon its downward movement, a U shaped deflector mounted inside the web opposite the grab at its web catching position and with the arms of the deflector at each side of the toothed head whereby the web is deflected toward the grab to insure its engagement therewith.
6. In a circular knitting machine the combination of a grab comprising a toothed head and a vertical rod mounted to slide at one side of the web to permit the teeth of the head to catch in the web upon the downward movement of the grab, yielding means for causing said downward movement, teeth on the said rod, a pawl carrier mounted to slide on said rod and means for giving such pawl carrier a reciprocating movement, a pawl pivotally mounted on said carrier and yieldingly held toward said teeth and acting in coöperation with said teeth intermittently to elevate the grab, a latch to maintain the grab in its web catching position, and pattern controlled means to release the latch allowing the grab to descend and to hold the pawl out of coöperation with said teeth during said descending movement and then to restore the pawl to coöperation with said teeth.
- In testimony whereof, I have signed my name to this specification, in the presence of two subscribing witnesses.
